UNITED STATES PATENT OFFICE.

WILHELM LINNMANN, JR., OF ESSEN-ALTENESSEN, GERMANY.

APPARATUS FOR SEPARATING LIQUIDS OF DIFFERENT GRAVITY.

Application filed November 22, 1926, Serial No. 149,850, and in Germany June 8, 1926.

My invention relates to improvements in apparatus for separating liquids of different gravity, such for example as waste-water and benzol, and more particularly in apparatus having an inlet to the separating tank and an outlet therefrom, and provided with means for automatically closing the outlet when a certain amount of benzol has been collected therein. The object of the improvements is to provide an apparatus of this class which is simple in construction and reliable in operation, and with this object in view my invention consists in providing the delivery pipe from the tank at its inlet with a portion opening into a vertical tubular member located within the tank and covered at its top by a cap or hood located with its bottom part below the top part of said tubular member and adapted to be closed by the benzol rising within the tank and to close the outlet by the pressure produced therein.

For the purpose of explaining the invention several examples embodying the same have been shown in the accompanying drawings in which the same letters of reference have been used in all the views to indicate corresponding parts. In said drawings,

Fig. 1 is a sectional elevation showing the tank,

Fig. 2 is a detail sectional elevation showing the delivery pipe and the means for controlling the flow of the liquid therefrom, the parts being shown in the position in which the heavy liquid such as water is being delivered from the tank,

Fig. 3 is a similar detail sectional elevation showing the parts in the position in which the delivery pipe has been closed, and

Figs. 4 to 8 are elevations similar to those shown in Figs. 2 and 3 and showing modifications of the apparatus.

In describing the invention reference will be made to an apparatus for separating benzol from waste-water. But I wish it to be understood that my invention is not limited to such use.

In the example shown in Figs. 1 to 3, my improved apparatus comprises a tank *a* having an inlet *b* and a delivery pipe *c* for waste-water, the delivery pipe being bent to provide a water seal and having its top part directed upwardly and providing a seat for a float valve *f* provided with a packing ring *g*. The tank *a* is provided with a vertical partition wall *o* extending from the

top to a point away from the bottom thereof and formed in its upper part with an opening *p*. By the said partition wall the tank *a* is divided into two sections *q* and *r*, the section *q* receiving the water from the inlet pipe *b*, and the section *r* enclosing the inlet end of the delivery pipe *c* and the means for controlling the discharge of the water from the tank.

The inlet end of the pipe *c* and the float valve *f* are surrounded by a vertical tubular member *d* open at its top and bottom and covered at its top by a cap or hood *e* the bottom part of which is located below the top part of the pipe *d* and at a higher level than the top part of the pipe *c*.

In the operation of the apparatus waste-water containing benzol is admitted through the pipe *b* and into the chamber *q* in which the benzol is separated from the water and by reason of its lower specific gravity rises to the top of the water. Thus only water is collected within the chamber *r*. As the water rises within the tank, the bottom part of the tubular member *d* is first closed, and thereafter the water rises so far that it flows through the opening *p* into the top part of the chamber *r*. Thus only water rises within the tubular member *d*, while the benzol

collected on the surface of the water flows also into the upper part of the chamber *r*. At the beginning of the operation there will be hardly any benzol on the surface of the water, so that at the beginning the liquid is at the same level within the chamber *r* and the tubular member *d*, as has been indicated in Fig. 2.

When the water rises above the inlet end of the pipe *c* the float *f* is unseated, so that the water is delivered through the pipe *c*. Gradually the layer of benzol on the surface of the water will increase, and by reason of the lower specific gravity of the benzol the level of the liquid will be higher outside the tubular member *d* than inside the same, as has been indicated in Fig. 3 in which the water has been indicated by comparatively wide lines, while the benzol has been indicated by narrow lines.

Thus the cap *e* will gradually be closed at its bottom, so that the air is confined below the same. Thereby the pressure of the air below the hood *e* will rise and prevent the unseating of the float valve *f*, whereupon the discharge of water from the tank is interrupted.

The modification shown in Fig. 4 is simi-

lar to the one shown in Figs. 1 to 3, and the same letters of reference have been used to indicate corresponding parts. However the tubular member *h* surrounding the float 5 valve *f* and the inlet end of the pipe *c* is constructed in a slightly different way, the said member being in the form of a pipe only at its top part, and secured to the side wall of the tank with its bottom part. The

10 operation of the apparatus is the same as has been described with reference to Fig. 1.

In the modification shown in Fig. 5 the float *f* is provided with a hollow extension *i* projecting downwardly and into the pipe *c*.

15 Thereby the float valve is more readily raised from its seat. If after slightly lifting the float the water flows into the pipe *c* which

so far was only partly filled, the buoyancy of the float is increased. Otherwise the con-

20 struction is the same as that described with reference to Figs. 1 to 3, and the same let-

ters of reference have been used to indicate corresponding parts.

In Fig. 6 I have shown a modification 25 in which the delivery pipe *c* is enlarged at its top into the form of a cup *k* receiving the float *f*. The float is elevated when the waste-water flows above the upper margin of the said cup. When however the benzol 30 rises to the lower margin of the hood *e*, and the water rises within the tubular member *h*, the air contained therein is compressed, and the level within the tubular member is lowered so far that the water does not flow any 35 more into the cup *k*. To assist the rising of the float I prefer to provide the hood with a tubular member *m* projecting downwardly therefrom into the annular space provided between the float *f* and the wall of the 40 cup *k*.

In the modification shown in Fig. 7 the float *t* is annular in form, and it carries a valve disk *s* adapted to close the pipe *c*.

In Fig. 8 a modification is shown in which 45 an annular float *u* is provided, which is located outside the tubular member *h*. In addition the valve member is in the form of a float *v* connected with the annular float *u* by a cap-shaped member *w*.

50 While in describing the invention reference has been made to particular examples embodying the same I wish it to be understood that my invention is not limited to the constructions shown in the drawings, and 55 that various changes may be made in the general arrangement of the apparatus and the construction of its parts without departing from the invention. For example the float valve *f* may be omitted, in which case 60 the discharge of the water is interrupted by the level of the water falling below the top of the pipe *c*.

I claim:

1. An apparatus for separating liquids of different specific gravities, comprising a tank having an inlet, a container closed at its top and communicating with said tank near its bottom, and an outlet projecting into said container, said container communicating at its top with said tank through a passage 70 extending into said tank downwardly and to a point above the level of the inlet end of said outlet.

2. Apparatus for separating liquids of different specific gravities, comprising a tank 75 having an inlet and an outlet, a container within said tank open at its top and communicating with the tank near the bottom thereof, said outlet comprising a pipe projecting into said container to a point below 80 the top thereof, and a hood covering the top of said container and having its bottom part located below the top part of said container and above the level of the inlet end of said pipe.

3. An apparatus for separating liquids of different specific gravities, comprising a tank having an inlet, a container closed at its top and communicating with said tank near its bottom, an outlet projecting into said container, said container communicating at its top with said tank through a passage extending into said tank downwardly and to a point above the level of the inlet end of said outlet, and a float valve on said outlet. 90

4. An apparatus for separating liquids of different specific gravities, comprising a tank having an inlet, a container closed at its top and communicating with said tank near its bottom, an outlet projecting into said container, said container communicating at its top with said tank through a passage extending into said tank downwardly and to a point above the level of the inlet end of said outlet, and a float valve on said outlet, 100 said outlet being formed at its inlet end with a cup receiving said float valve.

5. An apparatus for separating liquids of different specific gravities, comprising a tank having an inlet and an outlet, a tubular member within said tank open at its top and communicating with the tank near the bottom thereof, said outlet comprising a pipe projecting into said tubular member to a point below the top thereof, a hood covering the top of said tubular member and having its bottom part located below the top part of said tubular member and above the level of the inlet end of said pipe, and a partition within said tank separating said tubular member and hood from the inlet side of said tank and formed at its upper part with a hole. 110

In testimony whereof I hereunto affix my signature.

WILHELM LINNMAN, JR.
